(57) **CLAIM**

The ornamental design for a lighting fixture as shown and described.

DESCRIPTION

This application is related to commonly assigned, co-filed U.S. design patent application Ser. No. 29/792,009, filed on Feb. 25, 2022, by Adami et al., entitled "Lighting Fixture"; commonly assigned, co-filed U.S. design patent application Ser. No. 29/792,012, filed on Feb. 25, 2022, by Adami et al., entitled "Bench"; commonly assigned, co-filed U.S. design patent application Ser. No. 29/792,013, filed on Feb. 25, 2022, by Adami et al., entitled "Path Light"; and commonly assigned, co-filed U.S. design patent application Ser. No. 29/792,014, filed on Feb. 25, 2022, by Adami et al., entitled "Bench End", which applications are incorporated herein by reference in their entireties.

FIG. 1 is a front right perspective view of a lighting fixture, according to the new design;

FIG. 2 is an enlarged front elevational view thereof;

FIG. 3 is an enlarged right side elevational view thereof;

FIG. 4 is an enlarged left side elevational view thereof;

FIG. 5 is an enlarged rear elevational view thereof;

FIG. 6 is an enlarged top view thereof;

FIG. 7 is an enlarged bottom view thereof;

FIG. 8 is a front right perspective view thereof, but shown illuminated;

FIG. 9 is an enlarged front elevational view thereof;

FIG. 10 is an enlarged right side elevational view thereof;

FIG. 11 is an enlarged left side elevational view thereof;

FIG. 12 is an enlarged rear elevational view thereof;

FIG. 13 is an enlarged top view thereof; and,

FIG. 14 is an enlarged bottom view thereof.

The broken lines in the drawings illustrate portions of the lighting fixture which form no part of the claimed design. The long dash-short dash lines in the drawings represent a boundary of the claimed design.

1 Claim, 12 Drawing Sheets
